UNITED STATES PATENT OFFICE

WALTER J. BINDER, OF TRENTON, NEW JERSEY

OVERSHOE

Application filed June 15, 1928. Serial No. 285,601.

A principal object of this invention is to provide an overshoe, intended more particularly for emergency use, which is of novel construction and embodies characteristics 5 and advantages not heretofore found in footwear of the general class to which the invention relates.

A further object of the invention is to provide an overshoe which is satisfactorily 10 adapted for the performance of its intended function yet which is extremely light in weight, compact, and thus adapted to be carried in a handbag or even in the pocket with a maximum of convenience and without occupying much space, and which is so constructed as to readily adhere to and remain 15 in position upon shoes of various sizes; thus by manufacturing the overshoe in but a relatively small number of sizes the entire range 20 of sizes of shoes normally worn may be covered while the dealer is enabled to meet the needs of the purchasing public by carrying in stock only a few different sizes of the overshoe.

A still further object of the invention is to provide an overshoe of the character aforesaid which is relatively durable so that it may be worn several times, or for a relatively long period of time continuously, before it becomes unserviceable, and to provide such an overshoe so constructed that if cut or torn the hole will not enlarge itself with undue rapidity and thus render the overshoe useless in a very short period of time, a defect which 35 is necessarily present in at least one type of emergency overshoe with which I am familiar.

Further objects, advantages and novel features of construction comprehended by my 40 invention are hereinafter more particularly mentioned or will be apparent from the following description of certain forms of the invention as illustrated in the accompanying drawing.

45 In the said drawing Fig. 1 is a side eleva-

tion of a preferred embodiment of my invention in position on a shoe; Fig. 2 is an enlarged perspective view of the element which constitutes the base or body of the overshoe and prior to its being coated with elastic, 50 flexible water-resistant as hereinafter described, and Fig. 3 is a similar view of the finished overshoe shown in Fig. 1 partially broken away into section to better illustrate the construction. Fig. 4 is a transverse section through the overshoe removed from the shoe and showing a slightly modified construction; Fig. 5 is a view substantially similar to Fig. 1 showing an overshoe constructed in accordance with another modified form 55 of the invention and Fig. 6 is a view showing a still further modified form of the invention with a portion of the overshoe broken away into section. The same numerals are used to illustrate corresponding parts in the 60 several figures.

Referring now more particularly to the form of invention shown in Figs. 1 to 3 inclusive, it will be apparent that the overshoe 1 is of generally hollow frustro-conical form, open at its larger end and tapering toward its smaller and closed end, so that when drawn over the toe of the boot or shoe it will enclose the same, form a snug fit thereon and extend well up on the vamp so as to afford adequate protection to that part of the shoe most liable to penetration by dampness or water. To insure this snugness of fit, the overshoe is so constructed as to afford a relatively large capacity for transverse or cross-wise stretch or expansion and to this end in the manufacture of the overshoe the base or body 2 is first formed by knitting from suitable yarn, preferably through the medium of a suitable knitting machine, or by weaving a special fabric having a relatively great capacity to stretch in at least one direction. The body may either be knitted or woven singly as shown in Fig. 2 so as to produce a 75 complete unitary structure without seams, or 80

a continuous tube may first be knitted or woven and then cut off into suitable lengths and one end of each of the pieces so formed then seamed together so as to produce the 5 base or body, or the fabric may be woven or knitted flat and then suitably cut and seamed so as to form the base or body in such manner that its maximum stretching capacity is in a generally transverse or crosswise direction. 10 Thus, irrespective of its particular method of manufacture, the base or body resembles generally the toe of an ordinary sock or stocking and due to its method of formation, that is, by knitting, weaving or the like, has a relatively 15 large capacity for stretching or expansion both transversely or crosswise and, what is less important for the purposes of the invention, longitudinally, and is thus adapted to adhere quite snugly to any object such as 20 the toe of a boot or shoe of suitable size over which it may be pulled.

The base having been constructed as described is then placed on a form preferably approximating the shape of the toe of a boot 25 or shoe and impregnated or coated with a suitable elastic, flexible and water-resistant material such as rubber, bakelite, cellulose lacquers or the like, which are applied in any suitable way as by spraying or by dipping 30 the base in the coating material. If rubber or rubber-like materials are used for the coating it will be preferable though not necessary to vulcanize the coating after application to the base in any of the ordinary and well 35 known ways, thus producing the finished coating 3 which completely covers the exterior of the base and thoroughly impregnates the body thereof as well. I prefer to ordinarily form a small half-round bead or 40 thicker edging 5 adjacent the open end of the overshoe as the same is of assistance in maintaining the latter in proper position on the shoe; this bead may be formed in numerous ways as will be readily apparent to those 45 skilled in the art, for example, by rolling the end of the base 2 over on itself prior to the coating operation or by depositing an excess of the coating material adjacent the end of the base or in any other suitable manner.

50 It will of course be understood that the coating material is applied to the base when the latter is in unstretched or normal condition and further that for the most satisfactory results under conditions of use the elasticity of the coating material in the finished overshoe should approximate the elasticity or stretching capacity so that both the coating and the base will move unitarily when expanding or contracting. The result is that 55 the base member affords a firm but yielding support for the coating material at all times and whether in normal or in stretched condition, thus enhancing the durability of the overshoe as a whole and confining any cuts, 60 punctures or tears to the vicinity of the point

where they occur. This ability of my improved overshoe to localize and prevent the spreading of punctures, cuts or tears is an important advantage which is entirely absent from those forms of emergency footwear 70 heretofore suggested and which consist of solely a thin film of rubber or the like which, when the overshoe is in position on the boot or shoe, is in a state of considerable tension, so that immediately upon the occurrence of a 75 puncture, cut or tear the latter spreads from the point of its initial occurrence and immediately renders the overshoe entirely unserviceable.

If desired and in order to facilitate the 80 pulling of the overshoe over the toe of the shoe of the wearer small tabs 6 may be secured at diametrically opposed points on the inside of the overshoe at any suitable time in its process of manufacture so as to project a 85 little beyond the bead 5 and thus afford a convenient point to be gripped between the thumb and forefinger while the overshoe is being drawn into position.

Under most conditions I prefer to make the 90 coating 3 of uniform thickness substantially throughout its extent but, if desired, the thickness of the coating may be increased throughout that area of the overshoe which is designed to lie beneath the sole of the shoe 95 when in use to thereby provide greater wearing capacity throughout that portion or area of the overshoe which is normally subjected to the greatest amount of wear. In Fig. 4 100 I have shown an overshoe of this character, the coating 5 throughout that portion of the overshoe which normally encloses the upper part and sides of the toe of the shoe being of usual thickness and that portion which is designed to lie beneath the sole being of some- 105 what greater thickness as indicated at 3'.

The form of the invention shown in Fig. 5 is similar to that shown in Fig. 1 except for the omission of the tabs 6 and the provision of an elastic U-shaped strap 7 designed to extend rearwardly and upwardly from the open end of the overshoe and about the heel or quarter of the shoe to assist in retaining the overshoe in position. Under ordinary conditions the inherent elasticity of the overshoe 110 is entirely sufficient to maintain it in position on the shoe but under certain circumstances the provision of the strap may be found desirable and is thus within contemplation of my invention.

In Fig. 6 I have shown a still further modified form of the invention in which the base is so shaped as to enclose the vamp, counter and a portion of the upper of the shoe as shown but is provided with an opening 8 for the passage of the heel H, the base being of course coated with the elastic flexible water-resistant material as in the other forms of the invention heretofore described.

It will thus be apparent that overshoes 130

constructed in accordance with my invention may be manufactured at a very low cost for the body or base can be formed very cheaply from relatively inexpensive yarn and then 5 coated with the elastic, flexible water-resistant material at a minimum of expense with resulting production of an article which can be sold at a popular price. On the other hand, due to the improved and peculiar 10 construction of the overshoe by which a maximum of transverse elasticity or stretching capacity is obtained, the overshoe may be satisfactorily applied to shoes differing considerably in size and when so applied will remain 15 in position thereon under all ordinary conditions of use and effectually prevent the penetration of moisture or dampness into the toe and that portion of the sole of the shoe which contacts with the pavement. As heretofore 20 explained the flexible elastic coating and the yielding body of the overshoe expand and contract together when the overshoe is placed upon or removed from the shoe and thus work in unison with each other while, because of 25 the support afforded to the coating, which when the overshoe is in use is in tension, a tear, puncture or cut in the overshoe is localized and prevented from extending itself and thereby rendering the overshoe unserviceable 30 almost as soon as the puncture, tear or cut occurs.

When removed from the shoe a pair of these overshoes may be folded or rolled into a very compact package which may be readily 35 carried in the pocket, handbag or the like so as to be always available for use when required, while because of the effective support afforded to the coating by the base at all times and under all conditions the durability of the overshoes is materially increased so that they may be worn for a number 40 of times before they have to be discarded and replaced with a new pair. Moreover, because of the very low price at which overshoes embodying the principles of my invention 45 may be manufactured and sold, several pairs may be readily owned by a single individual and kept in various locations ready for use should the necessity arise, as, for example, the owner's home and place of business, or they may be purchased when and as required in traveling or the like and either thrown away after being worn once or else preserved for subsequent use.

If desired the coating may be painted or otherwise treated so as to imitate foxing or to produce any suitable design thereon to enhance the appearance and attractiveness of the overshoe. Moreover, it will be apparent 55 that because of the improved method of construction of the overshoe forming the subject of the present invention, the necessity of separately forming and then securing a number of separate parts together by vulcanization in 60 a mold or otherwise as has hitherto been

required in the manufacture of most styles of rubbers and overshoes is entirely avoided.

While I have herein illustrated and described with considerable particularity certain forms of overshoes constructed in accordance with the principles of my invention I do not thereby intend to limit myself specifically thereto as minor changes and modifications may be made in the design, construction and arrangement of the various 70 parts and the overshoes formed in different shapes to better adapt them to the prevailing fashions in shoes for men, women and children or for other purposes as may be desired without departing from the spirit and scope 75 of the invention as defined in the appended claims.

Having thus described my invention, I claim and desire to protect by Letters Patent of the United States:

1. An overshoe of the class described embodying a tubular base of relatively loosely knitted or woven fabric, closed at one end and open at the other and capable of being stretched in all directions from its normal condition, and a coating of elastic, flexible water-resistant material disposed on the exterior of the base and impregnating the body thereof and having substantially similar stretching properties as the base whereby 90 when the overshoe is drawn over the toe of a shoe the base and the coating stretch substantially unitarily to accommodate themselves to the configuration of the shoe and 95 snugly adhere thereto, said fabric base being highly elastic and arranged to stretch transversely substantially the same as the elastic covering to permit the overshoe to fit a plurality of widths of shoes without impairing the reinforcement of the elastic covering. 105

2. An overshoe of the class described comprising a tubular base of relatively loosely knitted or woven fabric having the capacity of stretching transversely from its normal condition and closed at one end and open at the other, and a coating of elastic, flexible water-resistant material disposed on the exterior of the base, impregnating the body thereof and adapted to stretch uniformly and substantially unitarily with the base in a 110 transverse direction whereby the overshoe is adapted to fit a plurality of widths of shoes without impairing the reinforcement of the coating, said coating being thickened throughout a predetermined area adapted to 115 lie beneath the sole of the shoe when the overshoe is drawn over the toe thereof. 120

3. An overshoe of the class described comprising a single piece tubular base of relatively loosely knitted or woven fabric having the capacity of stretching transversely from its normal condition and closed at one end and open at the other, and a coating of elastic, flexible water-resistant material disposed on the base, impregnating the body thereof and 125 130

adapted to stretch uniformly and substantially unitarily with the base in a transverse direction whereby the overshoe is adapted to fit a plurality of widths of shoes without impairing the reinforcement of the coating, said coating being thickened throughout a predetermined area adapted to lie beneath the sole of the shoe when the overshoe is drawn over the toe thereof.

10 In witness whereof I have hereunto set my hand this 12th day of June, 1928.

WALTER J. BINDER.
